UNITED STATES PATENT OFFICE.

FRED B. PARKS, OF GRAND RAPIDS, MICHIGAN.

PLIERS.

SPECIFICATION forming part of Letters Patent No. 653,920, dated July 17, 1900.

Application filed April 13, 1899. Serial No. 712,951. (No model.)

To all whom it may concern:

Be it known that I, FRED B. PARKS, a citizen of the United States, residing at Grand Rapids, in the county of Kent and State of Michigan, have invented certain new and useful Improvements in Pliers, of which the following is a specification.

My invention relates to improvements in pliers for inserting plugs in punctures through pneumatic tires; and its object is to provide pliers with which the plug may be held and inserted through the puncture and in position to close the puncture without danger of increasing the size of the puncture and the pliers removed without danger of withdrawing the plug. I attain this object by the mechanism illustrated in the accompanying drawings, in which—

Figure 1 is an elevation of my pliers. Fig. 2 is a plan of the same; and Fig. 3 is a side view of a portion of the pliers and a section of a tire, showing the manner of inserting the plug.

Similar letters refer to similar parts throughout the several views.

My pliers are of ordinary construction, except as to the jaws, which are made long, slim, and are curved or bent, as shown in Figs. 1 and 3, to form a graceful curve from the points to about one-third of the distance to the head. The point of the lower jaw A must project about three-sixteenths of an inch beyond the end of the upper jaw B, as shown at a, so that when entering the puncture to insert the plug D, as shown in Fig. 3, the head d of the plug will be grasped by the jaws of the pliers, and the under jaw will enter the aperture far enough ahead of the upper jaw to form a perfectly-rigid support between the surface of the plug and the wall of

the puncture, while the upper jaw standing back of the lower jaw will be embedded in the soft rubber of the head of the plug, so that its point cannot come in contact with the tire to tear the puncture larger. The outer 45 surface of the jaws should be rounded, as indicated in the drawings, and both the outer and the inner surfaces should be polished as smooth as possible, so that they may be passed through the puncture with perfect ease and 50 without danger of tearing it larger and so that they may be withdrawn without danger of drawing the plug out with them.

C represents the head and handles of the pliers, which may be made in any of the ordinary forms of construction common to small pliers.

Having now fully described my invention, what I claim as new, and desire to secure by Letters Patent of the United States, is— 60

In bicycle-repair pliers, two members pivoted together at the point of crossing, a handle integral with, and projecting back from each member, a long slim tapering jaw integral with and projecting forward from each 65 member both of said jaws formed upon a uniform curve in the same direction, from the member to the point of the jaw so that the concave surface of one fits over the convex surface of the other and the end of the inner 70 jaw projecting beyond the end of the outer jaw, substantially as and for the purpose set forth.

Signed at Grand Rapids, Michigan, March 31, 1899.

FRED B. PARKS.

In presence of—

ANDREW ALLGIER,
A. W. JOANNES.
